CLAIM

The ornamental design for a vent, as shown and described.

DESCRIPTION

FIG. 1 is a front perspective view of a vent.

FIG. 2 is a front view of the vent shown in FIG. 1.

FIG. 3 is a back view of the vent shown in FIG. 1.

FIG. 4 is a right side view of the vent shown in FIG. 1.

FIG. 5 is a left side view of the vent shown in FIG. 1.

FIG. 6 is a top view of the vent shown in FIG. 1.

FIG. 7 is a bottom view of the vent shown in FIG. 1.

FIG. 8 is a back perspective exploded view of the vent shown in FIG. 1; and,

FIG. 9 is a front perspective exploded view of the vent shown in FIG. 1.

The broken line showing of a vent is included for the purpose of illustrating portions of the article and forms no part of the claimed design.

1 Claim, 5 Drawing Sheets
